UNITED STATES PATENT OFFICE

FREDERICK L. FULLER, OF ILION, NEW YORK, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed December 22, 1922. Serial No. 608,467.

This invention relates to improvements in cash registers or accounting machines and the totalizers employed therein and more particularly to the transfer or carrying mechanisms.

A broad object of the present invention is to provide a suitable mechanism for positively transmitting motion from each adding wheel of a lower order to the adding wheel 10 of next higher order when the lower order adding wheel has completed a full rotation.

More specifically it is an object of the present invention to provide a transfer mechanism comprising a trip pawl actuated by a trip device associated with the wheel of the lower order to set a transfer pawl in its transfer position, so that when a separately operated arm is oscillated during a regular operation of the machine the transfer pawl 20 describes a path which intercepts a tooth of the next higher order totalizer wheel thereby effecting a transfer.

Further objects of the present invention are to prevent accidental displacement of the 25 totalizer wheels when out of engagement with their actuating segments, to provide frictional means for retaining the components of the transfer mechanism in their set position and to preclude the possibility of over-carrying 30 of the totalizer wheel when the machine is subjected to improper usage.

With these and incidental objects in view the invention consists in certain novel features of construction and combination of 35 parts, the essential elements of which are set forth in appended claims, and a preferred form of embodiment of which is hereafter described with reference to the drawings 40 which accompany and form part of the specification.

Of said drawings:

Fig. 1 is a transverse sectional view of the machine to which this invention is applied 45 and shows the means for actuating the totalizers and the transfer arms for effecting transfers.

Fig. 2 is a view in front elevation partly in section of one of the totalizers, sections A, 50 B, C and D being transverse sections taken

at different distances from the shaft which supports the totalizer wheels.

Fig. 3 is a view showing the means for actuating the totalizer pinions, one of the arms for operating the transfer mechanism 55 and the associated complementary cams.

Fig. 4 is a view taken on the line 4-4 of Fig. 2 showing the totalizer in its normal position with relation to its actuator.

Figs. 5, 6 and 7 are views the same as Fig. 60 4 but with the operating parts in different positions.

Fig. 8 is a view of the transfer mechanism showing how transfers by transfers are effected.

Fig. 9 is a view in perspective of the components of the transfer mechanism illustrating their co-operative relationship.

In the accompanying drawings the improvements are shown in connection with a 70 machine of the general type fully shown in the pending applications for United States Letters Patent S. N. 263,125, filed November 19, 1918, and S. N. 283,720 filed Mar. 20, 1919, by Frederick L. Fuller as well as in the 75 British Patents 135,465; 140,363; 157,823; 157,824; 157,825, of July 11, 1921. Only such parts of the machine as are directly involved in the present invention are described herein, however, and reference should be 80 made to the applications and British Patents mentioned for any information desired as to the construction and operation of the rest of the machine.

Although the improvements have been 85 shown applied to the machines shown and described in the above cited applications and patents, it is to be understood that the improvements are capable of being applied to or embodied in accounting machines 90 generally without departing from the spirit of the invention.

Described in general terms the illustrative machine comprises a series of manipulative devices such as keys 20 operable to actuate 95 totalizing mechanism and mechanism for entering the items on a record strip.

The keys 20 are pivoted upon a rod 21 and resting upon the rear ends of the keys is a key coupler 22 pivoted at 23. When the 100

outer ends of the keys are depressed the coupler is rocked clockwise about its pivot and its nose 24 enters the notches 25 in the rear ends of the keys. The construction and purpose of key coupler mechanisms are well known in the art and need not be discussed herein.

As shown in Fig. 1, each key 20 is formed with an upwardly extending arm 26 carrying a stud 27 engaging a slot 28 in a plate 29 rigidly mounted in a frame 30 loosely mounted on the shaft 31. The slots 28 in plates 29 are graduated so that each of the keys will impart a different degree of movement to the frame 30. The plates are furthermore provided with arcuate slots 36 to permit the upward tilting of the cam plates without interfering with the rollers on the remaining unoperated keys. Secured to the frame 30 is a segmental rack 301. It is to be understood that the keys 20 are arranged in banks and that for each bank there is a differentially actuated frame 30 and its corresponding segment rack. Each segment is always in mesh with a pinion rigid with its corresponding item type wheel 32 and sets up a number which corresponds to the value of the key depressed.

Mounted below the item type carriers 32 and operable by the segmental racks hereinbefore mentioned are two totalizers 33 and 34, designated as totalizers "A" and "B" in Fig. 1 of the drawings. These may be utilized for the purpose of registering amounts for separate departments or clerks or in any other manner where it is desired to segregate the transactions into two classes and they have manipulative means associated therewith in order that either totalizer may be operated to register amounts of the various transactions.

Connected to the key coupler is a double rack 341, the connection being such that as the coupler is rocked by the keys the rack is raised or lowered, and drives a shaft 35 in such a manner that a complete reciprocation of the coupler will effect a complete rotation of the shaft. The shaft 35 carries cams and other devices for operating various parts of the mechanism. The mechanism for effecting rotation of the shaft has not been shown or described in detail because it is so old and well known in the art.

In the Fuller application No. 283,720 and British Patent 140,363 there are shown two special keys which are designated as "Clerks" or "Coupler lifting keys" (not shown in this application). These keys have certain functions, one of which is to serve as a means whereby the key coupler 22 may be partially raised to what may be termed the coupling position, in which position other keys representing the nature and amount of the transaction may be engaged with the coupler so that a complete operation of all the keys

so engaged with the coupler may be effected further by pressure applied to any engaged key. For further information relative to this construction reference may be had to the Fuller application just mentioned.

70

As shown more fully in the U. S. application S. N. 263,125 and the British patents previously mentioned the totalizers A and B are pivotally mounted between side frames so that their pinions are capable of being rocked into engagement with their respective actuators. The engagement of the totalizer A with its actuator is under control of its corresponding Clerk's or Coupler lifting key A while the totalizer B is placed in operation by means under control of its associated Clerk's or Coupler lifting key B. The engagement of the totalizer pinions with their associated actuators is effected during the time that the Clerk's or Coupler lifting key is depressed to its coupling position. Other keys may now be engaged with the coupler and upon further depressing one or more of such other keys the pinions will be actuated an amount commensurate with the value of the key or keys depressed. At the extreme end of the downward stroke, or, if desired, during the first part of the upward stroke of the keys, the selected totalizer is disengaged from the actuators and remains disengaged during the time the keys are returned to their normal position. This mechanism has been briefly explained here in order to understand more fully the present invention. However, for a more detailed description and showing reference may be had to application S. N. 263,125 and the several British patents.

130

The totalizers which are actuated during item entering operations are alike in all respects and a description of one totalizer will suffice. Referring to Fig. 2 the totalizer is mounted in a frame 40 formed with ears 41 and 42 supporting a shaft 43. Each totalizer wheel 44, to which is attached its associated totalizer pinion 45 and transfer disc 46, is loosely mounted upon this shaft. Below and parallel to the shaft just mentioned is a second shaft 47. This shaft carries the various devices for effecting transfers which will be explained more in detail hereinafter. In alignment with the shaft 47 are two bearings 48 and 49 which are adapted to receive studs carried by the side frames so that the totalizer frame may be oscillated bodily about the studs to move the totalizer wheels into or out of engagement with the actuating segments.

In the particular illustrative embodiment the totalizer comprises seven adding wheels 44 but this number may be altered to meet the requirements of a particular registering capacity. The adding wheels 44 and attached parts are practically duplicates and a description of one will suffice for all.

As shown in Fig. 2, each adding wheel has secured thereto at its right a disk 46 carrying a trip tooth 50 (Figs. 4 and 5) and to the right of each disk is secured a totalizer pinion 45 carrying ten teeth. It will be evident that if, for example, the units adding wheel is moved during an item entering operation so that it passes from its nine to its zero position, a unit must be transferred from the units to the tens wheel in order that the adding wheels will indicate the true amount. In general, provision must be made to transmit a unit to any higher denominational order each time that the next lower denominational order adding wheel passes from its nine to its zero position. At times it is necessary to effect transfers by transfers, and to make the problem clearer assume that 923 stands on the totalizer and 79 is to be added. At the end of the operation the totalizer wheels should, of course, indicate the total 1002. The units pinion during the operation will be moved nine steps by its actuator through "0" to its "2" position and, of course, a unit should be carried to the tens wheel. The tens pinion, however, by the movement of its actuator and the carrying mechanism will have passed from the "2" position to its "0" position and it will be necessary to carry a unit to the hundreds totalizer wheel, and in the same manner since the hundred totalizer wheel now stands at "0", a unit must be transferred to the thousands totalizer wheel in order to represent the correct total. In the present embodiment, if "one" should be transferred to a wheel of the next higher order while the same wheel is simultaneously being actuated by the actuators, a unit would be lost and an incorrect total would result. For this reason it is necessary that transfers be effected upon the upstroke of the keys, that is, when the totalizers pinions are out of mesh with the actuators. Furthermore, in order to effect transfers by transfers it is necessary to actuate the transfer mechanism successively, first the transfer mechanism between the units and tens order, then the transfer mechanism between the tens and hundreds order, etc.

With the above in mind, the method of effecting transfers between successive orders will now be explained. The mechanisms for effecting transfers between successive denominational orders are alike and in view of this fact the transfer mechanism between the units and tens order only will be described.

As stated before, each totalizer wheel 44 (Fig. 4) has attached to it at one side a transfer disk 46 which carries a trip tooth 50. Pivoted upon the shaft 47 is a trip pawl 51 (Figs. 2, 4 and 9) which is provided with a trip tooth 52 in the line of travel of the trip tooth 50 and adapted to engage therewith as the totalizer wheel passes from its "9" to its "0" position. The trip pawl 51 is further pro-

vided with a forward extension 53 carrying a stud 54 and a downwardly extending lug 55, the purpose of which will be explained later. Mounted on the shaft 47 and adjacent to the trip pawl 51 is an arm 56 which is reciprocated during each operation of the machine. The arm 56 has a forward extension 58 which carries a transfer pawl 59 carrying a transfer tooth 60 in the plane of the totalizer pinion 45 of the next higher denominational order, and will engage at times one of the teeth of the pinion to advance the totalizer pinion a unit when transfers are to be effected. As shown in Figs. 2, 4 and 9, the stud 54 which is secured to the trip pawl 51 passes through a clearance slot 61 formed in the forward extension 58 of the arm 56 and registers with a slot 62 in the transfer pawl 59. The means for attaching the transfer pawl 59 to the arm 56 is clearly shown in Figs. 2 and 9. Referring to these figures there will be seen a stud 64 which passes through the arm 56 and the transfer pawl 59. Between the head of the stud and the side of the arm 56 is a spring cone washer 65. The reason for this construction is that when the arm 56 is held, the transfer pawl 59 may be given a movement independent of the arm and at times when the arm 56 is given a movement, sufficient friction will be maintained between the faces of the arm 56 and the pawl 59 to insure that the both will move simultaneously.

The arm 56 is provided with a rearward extension 66 co-operating with an open slot 67 formed in a transfer operating arm 68. The transfer operating arms 68 are loosely mounted upon the shaft 31 and are provided with rearward extensions 69 (Figs. 1 and 3) carrying oppositely projecting anti-friction rollers 70 and 71. Upon the rotation shaft 35, which, as stated before, is given a complete rotation upon each operation of the machine, is secured a series of complementary cams 72 and 73 the peripheries of which are in contact with their associated anti-friction rollers. The pairs of cams 72 and 73 are spirally arranged about the shaft so that in a cycle of rotation of the shaft 35 the cams will actuate the transfer arms successively, first the tens transfer arm, then the hundreds, etc. It is, of course, necessary that a transfer arm be provided for each transfer device and in the illustrative embodiment six transfer arms are necessary; but it is evident that if the registering capacity of the totalizer be altered, a corresponding number of transfer arms must be provided.

The sequence of operations of the transfer devices is illustrated in Figs. 4, 5, 6 and 7, Fig. 4 showing the normal position of the totalizer. When a Clerk's or Coupler lifting key is depressed to its coupling position the shaft 35 will be partially rotated and the totalizer engaging mechanism brought into

operation so that the totalizer pinions are thrown into mesh with the segmental racks. Since the rollers 70 and 71 contact with the peripheries of the cams which are substantially concentric with the shaft 35, no movement of the arm 68 will take place at this time.

The totalizer pinions are shown in engagement with the segmental racks in Fig. 5. If, for example, "9" has been standing upon the units totalizer wheel and "1" is to be added thereto, the segmental rack 301 will advance the units pinion wheel one step and in so doing the totalizer wheel will pass from "9" to "0". The trip tooth 50 of the units totalizer wheel will now contact with the trip tooth 52 of the trip pawl 51 and rock it counter-clockwise as viewed in Fig. 5.

Since the rollers are still in contact with the concentric portion of the cams no movement of the arm 68 will take place and the arm 56 will be held in the position shown in Fig. 5 and as the trip tooth 50 depresses the trip tooth 52 of the trip pawl 51 the stud 54 will be carried upwardly, and by virtue of the pin and slot connection with the transfer pawl 59 will rotate the transfer pawl clockwise independently of the arm 56 about its pivot 64 until it occupies the position shown in Fig. 5. The stud 54 in its upward movement will impart no movement to the arm 56 since it will merely play in the clearance slot 61 provided for that purpose. The transfer pawl 59 is now in position for effecting a transfer to the totalizer pinion of the next higher order.

Near the extreme end of the down-stroke of the keys, or, if desired, during the first part of the up-stroke the totalizer pinions are disengaged from their segmental racks. See Fig. 6. The transfer operating arm 68 will hold the arm 56 and associated parts in the position shown in Fig. 5 while the totalizer is rocked bodily about the shaft 47 until it occupies the position shown in Fig. 6. At the proper time the roller 70 will engage the high portion 74 of the cam 73 to rock its associated transfer arm downwardly. As the transfer arm 68 begins its downward movement (Fig. 7) the arm 56 will be rocked counter-clockwise and carry with it the transfer pawl 59 by the means previously described, and the trip pawl 51. Upon further descent of the transfer operating arm 68 the lug 55 will contact with a portion of the totalizer frame and hold the stud 54 carried thereby against further movement.

(Fig. 7.) As the transfer operating arm 68 descends still further the forward extension 58 of the arm 56 will be raised still further upwardly, rocking the transfer pawl 59 counter-clockwise about the then fixed pivot 54 as well as about its own floating pivot 64, the transfer tooth 60 having in the meantime en-

gaged one of the teeth of the totalizer pinion of the tens order to advance it one step. As the transfer operating arm 68 returns to its normal position the parts will again assume the position illustrated in Fig. 4. The dash 73 dot line of Fig. 7 describes the path of the pawl 59 during the cycle of events just described.

Fig. 8 illustrates the condition which exists when a transfer by a transfer is to be effected. 75 To make this clearer assume that the tens wheel has been standing in its nine position and one has been added to it by the transfer operation just described. It is necessary, of course, that a unit be added to the hundreds 80 totalizer wheel. As a unit is being transferred to the tens totalizer wheel (Fig. 5) the totalizer pinion will advance from its nine to its zero position and in so doing will trip the pawl 51 associated with the transfer mechanism between the tens and hundreds totalizer wheel and set the transfer pawl 59 to perform a carrying operation. During the return or upstroke of the keys and after the transfer arm 68 associated with the transfer device between the units and tens order has been actuated, the transfer arm 68 associated with the transfer device between the tens and hundreds order will be actuated and advance the hundreds totalizer wheel one step in the 85 manner previously set forth.

To prevent accidental displacement of the totalizer pinions from their set positions when disengaged from their actuators as well as to assist in preventing over-rotation of the 90 totalizer wheels due to momentum there is provided a series of pawls 80. (Figs. 1, 2, and 4.) The pawls 80 are loosely pivoted upon a shaft 83 and urged rearwardly by 95 springs 81 so that their wedge shaped ends 82 engage the interdental space of the corresponding totalizer pinion.

Machines of this character are at time subjected to improper usage by persons who desire them to work improperly, and in order to effect a mis-operation of the machine they have operated the machine rapidly and with a considerable degree of force and violence. In rapid operations the sequence of events occur almost instantly and if considerable force 100 was utilized in operating the machine the transfer mechanism might impart such a rapid rotation to the totalizer wheels so as to cause the totalizer to over-carry, with a result that an incorrect registration would be indicated. To preclude the possibility of over-carrying the following mechanism is employed.

This mechanism is best shown in Figs. 6, 7 and 9. The transfer pawl 59 above mentioned is provided with a camming projection 85 which is in alinement with the holding pawl 80 associated with the same totalizer pinion as the transfer pawl 59. From Fig. 7 it will be evident that if the transfer arm 68 was

actuated rapidly the transfer tooth 60 would impart such a rapid rotation to the totalizer wheel as to over-carry. The camming projection 85 on the transfer pawl 59 is so positioned with relation to the rearward edge of

5 the pawl 80, that at substantially the time the trip tooth 60 becomes disengaged from the teeth of the totalizer pinion the camming projection 85 will contact with the rearward edge 10 of the pawl 80 so that the upper end of the pawl 80 will be cammed rearwardly to force the wedge shaped ends 82 into co-operation with the inter-dental spaces of the pinion, thus positively stopping the movement of the 15 totalizer pinion and preventing the possibility of over-throw.

Although the camming projection 85 has been shown in connection with the transfer pawl 59 with minor changes it can be formed 20 upon the rearward extension 58 of the arm 56 to accomplish the same purpose.

From the foregoing description it will be evident that during each operation of the machine the transfer pawls 59 are actuated by 25 their associated transfer operating arms irrespective of whether transfers are to be effected. When no transfers are to take place the rearward end of the arm 56 will be rocked downwardly about the shaft 47 as a pivot and 30 the transfer tooth 60 will be carried rearwardly but will not engage the teeth of the pinion wheel. The circular path described by the transfer tooth 60 of pawl 59 during a non-transferring cycle is shown by the dash dot 35 line 601 of Fig. 4.

Any suitable mechanism may be provided for resetting the totalizer pinions to zero, such as for example that shown in the Fuller application S. N. 263,125 and the British 40 patents.

Although this type of transfer mechanism has been shown in connection with a cash register it is not the desire to confine its application to this particular type of machine as it 45 is readily evident that with minor changes it may be applied to other forms of cash registers, accounting machines and other devices where transfer mechanisms are necessary and employed.

50 While the form of mechanism herein shown and described is admirably adapted to fulfill the objects primarily stated it is to be understood that it is not intended to confine the invention to the one form of embodiment herein shown and described as it is susceptible of embodiment in various forms all coming within the scope of the claims which follow:—

What is claimed is:

1. In a machine of the class described, the 60 combination with a plurality of registering elements, a transfer tripping projection movable with one of said elements, a trip pawl actuated by said tripping projection, an arm in juxtaposition to the trip pawl and carrying a transfer pawl, and a pin and slot

connection between said trip pawl and transfer pawl whereby the transfer pawl is set to transfer position relative to the arm when the tripping projection engages the trip pawl, said trip pawl and transfer pawl remaining 70 in set position until subsequent movement of said arm.

2. In a machine of the class described, the combination with a plurality of registering elements, a transfer tripping projection movable with one of said elements, a trip pawl actuated by said tripping projection, an arm in juxtaposition to the trip pawl, a transfer pawl pivotally carried by the said arm and having a transfer tooth in the path of a 80 pinion of a higher order registering element, a pin and slot connection between said trip pawl and its corresponding transfer pawl whereby the transfer pawl is set in its transfer position when the trip pawl is engaged 85 by the tripping projection, frictional means comprising a spring washer for retaining said transfer pawl and said trip pawl in their set positions, and means in connection with the said arm whereby the transfer pawl is 90 actuated during a regular operation to advance the higher order registering wheel a unit.

3. In a machine of the class described, the combination with a totalizer frame, a 95 plurality of registering elements, a transfer tripping projection movable with one of said elements, a trip pawl actuated by said tripping projection, an arm in juxtaposition to the trip pawl, a transfer pawl pivotally 100 mounted upon the said arm, frictional means comprising a spring washer for retaining said transfer pawl in its set position, a transfer operating arm adapted to move said trip pawl, arm and transfer pawl as a unit and a projection formed upon said trip pawl adapted to engage the totalizer frame during its movement whereby further movement of the trip pawl will be prevented while the movement of the corresponding arm and 105 transfer pawl continues.

4. In a machine of the class described, the combination with registering elements of different denominational orders, transfer mechanism comprising a tripping projection movable with a lower order registering element, a pivoted trip pawl, an arm mounted on the pivot of said trip pawl, a transfer pawl pivotally mounted on said arm, and a frictional means between the arm and transfer pawl whereby the arm and transfer pawl may move either in unison or the transfer pawl may be given a movement relative to 115 said arm.

5. In a machine of the class described, a 125 transfer lever adapted to be rocked on each operation of the machine, a pawl pivoted on said lever and normally adapted to move as a unit with said lever, and means for preventing said unitary movement upon rocking 130

of the lever and providing a fixed pivot for said pawl at a point removed from the fulcrum of said transfer lever.

6. A device according to claim 5 in which said fixed pivot is provided eccentric to the point of pivot of said pawl on said lever whereby movement of said lever causes a compound movement of said pawl about both pivots.

7. In a machine of the class described, comprising a main operating shaft, totalizer wheels of higher and lower orders and actuators therefor, the combination of a pivoted transfer element including a main lever, a trip member pivoted coaxially therewith, and an actuating pawl, means carried by a wheel of lower order for moving said trip member about its pivot in one direction and simultaneously rocking said pawl in the opposite direction, means for rocking said transfer element on each operation of the machine and means for causing said rocking movement to operate said pawl to introduce a unit in a wheel of higher order and simultaneously restore said pawl and said trip member to their normal relative positions.

8. In a device of the class described a series of totalizer wheels, actuators therefor, a transfer element normally moved about one axis on each operation of the machine, a shiftable axis for said element, means controlled by a wheel of lower order for shifting said last mentioned axis, and means for causing said element to move about said last mentioned axis.

9. In a machine of the class described, a pair of totalizer elements, and a transfer unit cooperating with said elements, comprising a lever, a pawl pivoted on said lever, and a member movable by one of said elements and adapted to transmit its movement in part to said pawl to modify the cooperative relation between said lever and pawl during an operation of the lever.

10. In a machine of the class described, the combination with registering elements including totalizer pinions of different denominational orders, transfer mechanism comprising a trip pawl, an arm carrying a transfer pawl, said transfer pawl being shiftable on said arm by said trip pawl, a transfer operating arm for transferring a unit to a higher order when the registering element of a lower order completes a rotation, said operating arm serving to restore said transfer pawl if it has been shifted, a pivoted pawl normally engaging the teeth of the higher order totalizer pinion but allowing rotation thereof, and means formed on said transfer pawl for urging the corresponding pivoted pawl to engage the teeth of the totalizer pinion whereby further rotation of the pinion will be prevented.

11. In a machine of the class described, the combination with registering elements in-

cluding totalizer pinions of different denominational orders, transfer mechanism comprising a trip pawl, a transfer pawl and transfer operating arm for transferring a unit to a higher order when the registering element of a lower order completes a rotation, said transfer pawl being shiftable on said arm by said trip pawl, a pivoted pawl normally engaging the teeth of the higher order totalizer pinion but allowing a free rotation thereof, and a camming projection carried by the transfer pawl adapted to cam the pivoted pawl to engage the teeth of the totalizer pinion whereby further rotation of the pinion will be prevented.

12. In a totalizer, a transfer lever, a pawl carried by said transfer lever, said pawl having an active and an inactive position, a member for placing said pawl in active position means for moving said lever and pawl as a unit when said pawl is in its inactive position, said member causing said last recited means to produce relative moment between the lever and pawl during the active stroke of the lever when said pawl is in its active position, to restore the pawl to its inactive position.

13. In a machine of the class described, the combination with a main operating shaft, a totalizer comprising wheels of higher and lower order, a transfer operating lever, means carried by said main shaft for rocking said lever on each operation of the machine, a transfer arm pivotally mounted on a fixed support and directly connected to said lever for movement thereby, a pawl carried by said arm normally in an inactive position, and means operated by a totalizer wheel of lower order to positively move said pawl into an active position whereby an operation of the transfer arm will add a unit in the wheel of higher order, said pawl being restored to its normal position relative to said arm by said means during the active stroke of the arm.

14. The combination with rotatable adding elements and actuators therefor, of a transfer element movable about one axis when no transfer is to be effected said element being moved about another axis to condition the same for effecting a transfer, and a device actuated by an adding element of lower order for controlling said last mentioned movement of the transfer element, and restoring the same to normal position.

15. In a totalizer, the combination of a main operating mechanism, of totalizer wheels and pinions of higher and lower orders, a pivoted member carrying a pivoted transfer device, means operated by a totalizer wheel of a lower order for positively rocking the transfer device in one direction about its own pivot, and devices, comprising said pivoted member and said means under control of the main operating mechanism for giving the transfer device a compound movement in

an opposite direction relative to and in the path of a pinion of the next higher order.

16. A device according to claim 15 in which the said compound movement comprises first moving the transfer device about the pivot of the member and then rocking the transfer device about its own pivot.

17. In a machine of the class described, a totalizer comprising a plurality of elements 10 of denominational orders, and a transfer unit between successive orders of said totalizer, comprising a lever adapted to be rocked upon each operation of the machine, a transfer pawl mounted on said lever and adapted to 15 assume either an active or an inactive position, and frictional means for holding said pawl in either its active or inactive position said means controlling gradual restoration of said pawl to inactive position during its effective operation.

In witness whereof I have signed my name hereto this 19th day of Dec., 1922.

FREDERICK L. FULLER.
